Primary Examiner — Bao-Yen T Nguyen*Assistant Examiner* — Bethany Louise Mallino(57) **CLAIM**

The ornamental design for a clothing drying rack, as shown and described.

DESCRIPTION

FIG. 1 is a top perspective view of the design of a clothing drying rack showing the new design and illustrating the clothing drying rack in a fully-opened position.

FIG. 2 is another perspective view thereof.

FIG. 3 is a front view thereof.

FIG. 4 is a rear view thereof.

FIG. 5 is a top view thereof.

FIG. 6 is a bottom view thereof.

FIG. 7 is a right side view thereof.

FIG. 8 is a left side view thereof.

FIG. 9 is a front view thereof, illustrated in a collapsed position.

FIG. 10 is a top perspective view thereof, illustrated in a folded position.

FIG. 11 is a bottom perspective view thereof, illustrated in a folded position; and,

FIG. 12 is an enlarged view of portion 12 shown in FIG. 1. The dot-dash broken lines depict the boundaries of the enlargements that form no part of the claimed design.
